CLAIM

The ornamental design for scissors, as shown.

DESCRIPTIONFIG. 1 is a top plan view of the scissors of the invention;
FIG. 2 is a right end view of the scissors of FIG. 1;
FIG. 3 is a left end view of the scissors of FIG. 1;
FIG. 4 is a front view of the scissors of FIG. 1;
FIG. 5 is a bottom plan view of the scissors of FIG. 1; and
FIG. 6 is a rear view of the scissors of FIG. 1.**1 Claim, 2 Drawing Sheets**FIG. 1

1

**REEXAMINATION CERTIFICATE
ISSUED UNDER 35 U.S.C. 307**

THE PATENT IS HEREBY AMENDED AS
INDICATED BELOW.

2

AS A RESULT OF REEXAMINATION, IT HAS BEEN
DETERMINED THAT:

The single design claim is cancelled.
